(57) **CLAIM**

The ornamental design for a baby cocoon, as shown and described.

DESCRIPTION

FIG. 1 is a front, top, right side perspective view of a baby cocoon, showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, in a position of use. The broken lines are shown for the purposes of illustrating environmental subject matter that forms no part of the claim.

1 Claim, 6 Drawing Sheets

FIG. 1

FIG. 2

FIG. 3

FIG. 4

FIG. 5

FIG. 6

FIG. 7

FIG. 8
